Patented Aug. 12, 1919.

FIG. 1.

FIG. 2.

UNITED STATES PATENT OFFICE.

JOHN WOLF, OF TOPEKA, KANSAS.

LOCK.

1,312,601.

Specification of Letters Patent. Patented Aug. 12, 1919.

Application filed May 12, 1919. Serial No. 296,374.

To all whom it may concern:

Be it known that I, JOHN WOLF, a citizen of the United States, residing at Topeka, in the county of Shawnee and State of Kansas, have invented certain new and useful Improvements in Locks, of which the following is a full, clear, and exact description, reference being had to the accompanying drawings, forming a part hereof.

10 The present invention is directed to improvements in locks, and particularly to trunk locks, having for its object to provide a key-operated lock which will be simple and durable, one that will withstand considerable abuse with the rough handling of the trunk, and one possessing further and other advantages better apparent from the following detailed description in connection with the accompanying drawings in which—

20 Figure 1 represents a top plan of a wardrobe trunk showing my invention applied thereto; Fig. 2 is a front elevation of the upper end of the trunk; Fig. 3 is a somewhat enlarged longitudinal section through the lock on the line 3—3 of Fig. 1; Fig. 4 is a view similar to Fig. 3, showing however in side elevation the casing in which the latch-bolt is mounted; Fig. 5 is a top plan of the keeper and the fitting to which 30 is hinged the leaf or casing in which the latch-bolt is mounted; Fig. 6 is a bottom plan of the casing or locking leaf in which the latch-bolt is mounted; Fig. 7 is a top plan of the locking leaf or latch-bolt casing 35 still further enlarged, a portion of the top wall being broken away; Fig. 8 is a bottom plan of the locking leaf with the bottom wall removed to expose the interior operating members; Fig. 9 is a longitudinal middle

40 section on the line 9—9 of Fig. 7, with the latch-bolt in side elevation; Fig. 10 is a similar view with the latch-bolt however in section; Fig. 11 is a detached bottom plan view of the key-actuated dog by which the bolt is withdrawn from the keeper; Fig. 12 is an edge view of Fig. 11; and Fig. 13 is a cross-section on the line 13—13 of Fig. 5.

Referring to the drawings, T represents the main section of a wardrobe trunk, T' the shorter section hinged thereto, and L, 50 the top lid hinged to the section T' and adapted to be locked to the section T, as well understood in the art. The lock A by which the lid L is locked to the trunk section T forms the subject-matter of the present invention, the details of the lock being shown in Figs. 5 to 13 inclusive. Referring to said figures, 1 represents the keeper member of the lock, the same being secured to the top of the trunk section T, said keeper being 60 brought into coöperating relation to the plate or mounting 2 secured to the lid L, said plate being provided with side walls or wings 3 and serving as a mounting for the locking hinge-leaf or latch-bolt casing 65 4, the latter being protected by the walls 3 when the leaf is swung against the plate to bring the latch-bolt 5 thereof into position for locking with the keeper 1. The leaf 4 is secured between the terminals of the walls 3 farthest removed from the keeper, by a hinge-pin 6, said leaf being automatically forced outwardly upon the withdrawal of the latch-bolt 5 from its keeper 1, by a flexed spring 7 having one end secured to 70 the bottom of the plate 2 adjacent to the hinge axis of the leaf, the free end of the spring operating through a slot or opening O formed in the plate and engaging the bottom of the leaf. The latch-bolt 5 is provided with, or forms the outer terminal of a frame or yoke 5' the inner cross-member of which carries a pair of lugs 8 between which the yoke is engaged by the adjacent 75 terminal of a compression spring 9 the opposite end whereof is received by a socket h adjacent the hinge axis of the leaf 4. The leaf 4 is in effect a casing or hollow member the inner and outer walls whereof are connected by a brace pin or strut 10, there being disposed between said strut and the cross member of the yoke, a post 11 for receiving the socket of the stem k of a suitable 80 key inserted into the leaf through the key-

55 60 65 70 75 80 85 90

hole *m*, the key-stem being provided with a suitable bit 13, as well understood in the art. The ends of the cross member of the yoke 5' engage the side walls of the leaf 4, and the bottom of said cross member is provided with feet 12, 12, engaging the bottom wall of the leaf, this arrangement serving to guide the yoke in the leaf and prevent binding in any direction. The inner wall of the cross member of the yoke is provided with a guard 14 freely permitting the bit 13 of the key to pass by the same, but obviously arresting or preventing the passage of a key-bit to which said guard does not conform. Mounted rotatably on the post 11, and resting on the bottom or inner wall of the hollow leaf 4, is a dog 15 of a shape substantially as shown in Figs. 8, 11, and 12, one terminal of the dog being provided with a projection or tooth 16 adapted to be engaged by the enlarged terminal of the key-bit 13, and provided at an intermediate point along the edge thereof with a guard or lug 17 between which and the yoke-guard 14 the key-bit normally enters when once inserted into the key-hole, said lug 17 preventing the rotation of the key in the wrong direction. The opposite end of the dog is provided with a lug or finger 18 adapted to engage a lug 19 on the adjacent arm of the yoke 5' whereby the yoke with its bolt 5 is forced inwardly with a turning of the key in proper direction, and the bolt withdrawn or disengaged from the keeper 1. The valances 20 are secured to the section T' and lid L, a slight offset *n* being formed in the plate 2 to accommodate the thickness of the metal band from which the valance is constructed (Fig. 13).

The operation is simple and may be readily understood by reference to Figs. 7, 8 and 10. By inserting the stem *k* of a suitable key into the keyhole *m*, the bit 13 of the key will naturally enter between the lug or guard 17 of the dog 15 and the guard 14 of yoke 5' to which the bolt-head 5 is secured. By turning the key in the direction indicated by the arrows in Figs. 7 and 8, the key-bit 13 will freely pass the guard 14 of the yoke 5' and eventually strike or engage the tooth or projection 16 of the dogs 15, continued rotation of the key causing the bit 13 to oscillate still farther and turn the dog about the axis of the post 11 in proper direction to cause the finger 18 at the opposite end of the dog to press against the lug 19 of the yoke 5' and force the latter inward against the tension of the spring 9, thereby compressing the spring and causing a withdrawal of the bolt 5 from the keeper 1. Once the bolt is withdrawn from the keeper, the flexed spring 7 bearing against the inner or bottom wall of the hinged leaf 4 asserts itself, forcing said leaf or latch-bolt casing (now released from the keeper) outwardly, the

leaf oscillating about the hinge pin 7 and assuming a position substantially as shown by the dotted lines in Fig. 4. This unlocks the lock A and leaves the lid L free to be swung to open position. The withdrawal of the key of course permits the bolt-operating parts to resume their original position, the spring 9 forcing the bolt out of the leaf or casing 4. When subsequently the lid is swung to closed position, the bevel or inclined face *t* of the bolt will ride over the edge *e* of the keeper, thus compressing the spring 9 until the edge of the bolt passes off the edge of the keeper, after which the spring will automatically force the bolt under the keeper as well understood in the art. In this respect the action is not unlike that of the majority of latch-bolts known to the trade. Obviously, I may resort to many changes in details without affecting the nature or spirit of the invention.

Having described my invention what I claim is:

1. In a lock of the character described, a hinged casing, a latch-bolt traversing a wall 90 of the casing, a keeper for the bolt, a yoke secured to the bolt and operating in the casing, a post in the casing within the yoke, a dog mounted rotatably on said post and adapted to be rotated in a given direction by 95 the bit of a key inserted through a key-hole in the casing wall and passed over the arbor aforesaid, a guard on the yoke permitting rotation of the key in proper direction to rotate the dog, a guard on the dog preventing rotation of the key in the opposite direction, the parts being disposed relatively to the key-hole to allow insertion of the key-bit between the guards aforesaid, a tooth on the dog adapted to be engaged by the key-bit, a 100 lug on the yoke, a finger on the dog for engaging the lug with a rotation of the dog by the key, and a spring bearing against the yoke at a point opposite from the bolt, for forcing the yoke and bolt outwardly upon 105 release of the dog, whereby the bolt may enter the keeper with a closing movement of the casing.

2. In a lock of the character described, a keeper, a latch-lock casing hinged to oscillate about a fixed axis, the outer wall of the casing being provided with a key-hole, a post projecting from the opposite wall opposite the key-hole and adapted to be engaged by the socket of a key-stem provided 115 with a key-bit, a latch-bolt operating through a terminal wall of the casing and adapted to engage the keeper, a yoke secured to the bolt and operating in the casing, the cross-member of the yoke being provided 120 with a pair of lugs, a spring having one end bearing against the cross-member between said lugs and the opposite end against the adjacent end wall of the casing, a key-guard 125 on the cross member facing the bolt, a dog 130

mounted rotatably on the post and terminating respectively in a finger and a tooth, a guard or lug on the dog positioned relatively to the key-guard on the yoke to cause the 5 key-bit to come between it and said key-guard, a lug on one of the arms of the yoke engaged by the finger on the dog, the key-bit being adapted to engage the tooth on the dog and impart rotation thereto whereby

the yoke is forced toward the rear of the cas- 10 ing and the bolt withdrawn from engage-
ment with the keeper.

In testimony whereof I affix my signature, in presence of two witnesses.

JOHN WOLF.
